McMAHEN COMPANY, OF PHILADELPHIA, PENNSYLVANIA.

BEDSPRING BRACE.

Application filed September 19, 1927. Serial No. 220,360.

My invention relates to bed springs or spring mattresses and more particularly to a border brace adapted to prevent the edges thereof from sagging and the supporting 5 surface from swaying.

While my improved brace may be used on springs of various types, it is particularly adapted for use in conjunction with bed springs which depend upon a plurality of 10 coiled springs for their resiliency. The prevalent custom of sitting on the edge of the bed causes any type of spring to sag and destroys the uniformity of its supporting surface, thus lessening the comfortableness of 15 the bed as well as marring its general appearance. When the edge of a bed spring is depressed, the border wire moves inwardly as well as downwardly due to the fact that the coiled springs constituting the supporting 20 surface are tied together either by rigid connections or by small coiled springs.

The principal object of my invention is to provide a border brace which is adapted to assist the bed spring in returning the border wire to its normal position after being depressed, to provide means for limiting the upward movement of the surface of the bed 25 spring beyond its normal plane, and to prevent swaying of the supporting surface.

Devices for preventing the swaying of bed 30 springs and devices for assisting the bed springs in returning to their normal position have heretofore been produced but, to the best of my knowledge, all of such devices 35 cause the border wire of the springs to move outwardly when the spring is depressed and have other inherent defects. A further object of this invention is to provide a border brace which will overcome such defects and 40 will allow the border wire of a bed spring to move downwardly in substantially a vertical plane.

A still further object of my invention is to employ a closely coiled spring for yieldingly 45 holding the border brace in its normal position and for limiting the upward movement of the movable part of the brace.

These objects, and other advantageous 50 ends which will appear hereinafter, I attain in the following manner, reference being had to the accompanying drawings, showing a certain embodiment of my invention and an application thereof, in which

Figure 1 is a perspective view of a frag-

ment of a bed spring upon which my invention has been installed. 55

Figure 2 is a side view of an embodiment of my invention, showing the same in normal position, and

Figure 3 is a view of the device shown in 60 Figure 2 as same would appear when connected to a border wire and in fully compressed position, and also showing, in dot and dash lines, the relative position of the border wire and brace part connected thereto when 65 the brace is in its normal position.

Referring now in more detail to the drawings, I have shown the brace as having a horizontally disposed support 5 which is twisted and bent at 6 to form a connecting part 7 70 adapted to overlap and be secured to the side rail 8 of a bed spring. A link 9 has one end pivotally connected to support 5 at a point adjacent twist 6 while its other end is pivotally connected to a lever 10 having a part 75 11 extending horizontally rearwardly from its point of union with lever 9 while the main part of the lever extends upwardly at an angle and terminates in a hook 12 adapted to be clamped around the border wire 13 of 80 the spring.

A closely coiled spring 14 rests on the end of support 5, abuts the underside of horizontal part 11, and is secured in place by loops 15 and 16 encircling the ends of support 5 85 and horizontal part 11 and held against displacement by the loops passing, respectively, through notches 17 and 18 formed in these ends. Loops 15 and 16 are so proportioned that they hold the ends of spring 14 snugly 90 against support 5 and part 11, respectively. As spring 14 is wound in a tight spiral, it will thus prevent the other end of lever 10 from moving upwardly beyond a predetermined point and this point is determined to 95 be the normal plane of the supporting surface of the bed spring.

The bed spring shown in Figure 1 obtains its resiliency from longitudinal and transverse rows of helically wound coiled springs 19 connected to one another by small coiled springs 20 and carried by straps 21 secured to rails 8. The outer row of springs 19 are secured to border wire 13, in any suitable manner as by binding 22, and it therefore follows that the entire supporting surface of the bed spring may oscillate both longitudinally and transversely unless prevented 100 105

by some device. As the length of the bed spring is substantially greater than the width, longitudinal oscillations are not as frequently encountered as transverse oscillations. To overcome such oscillations, I attach one or more of my border braces to each side of the bed spring and find that two of such braces on each side give highly satisfactory results.

When springs of this character are moved, it is customary to grasp them by the border wire at either side of the spring, thus forcing the border wire inwardly and pulling same upwardly which oftentimes distorts it.

With my improved brace in position, the border wire is held against both inward and outward movement and consequently prevents the spring from being distorted. When the coiled springs adjacent the border wire are depressed, as by a person sitting on the edge of the bed, the border wire tends to move inwardly due to the action of the springs 20. My device allows the border wire to be compressed under the weight of the person but prevents it from moving inwardly.

Border braces heretofore produced have prevented the border wire from being forced inwardly but, in so doing, have forced same to swing outwardly when being depressed and thus putting unnecessary strain upon the spring structure and destroying some of its resiliency. In Figure 3, I have shown in dot-and-dash lines the positions of lever 10 and hook 12 when the device is in normal position and, in full lines, their positions when the device is fully compressed. It will be noted that, when the device is fully compressed, border wire 13 is substantially directly under its normal position and that it moves downwardly in substantially a straight line, as shown by dot-and-dash line 23, thus insuring far better service from the spring structure.

It is, of course, understood that the bed spring brace illustrated may be modified and changed in various ways without departing from the invention herein set forth and hereafter claimed.

I claim:—

1. A border brace including a support, a link pivoted to the support, a lever pivoted to the link, and a coiled spring secured to adjacent ends of the support and lever and acting as a stop therebetween.

2. A border brace including a support, a link pivoted to the support, a lever pivoted to

the link, and a coiled spring secured to adjacent ends of the support and lever and acting as a stop therebetween; the end of the link pivoted to the support being disposed at a considerably greater distance from the spring than is its other end.

3. A border brace including a fixed support, a link pivoted to the support, a lever pivoted to the link, and a coiled spring secured by its opposite ends to adjacent ends of the support and lever and acting as a stop therebetween, the link being so disposed relatively to the spring that the free end of the lever moves downwardly when acted upon by an outside force.

4. In a bed spring having a side rail and a border wire, a border brace including a support rigidly fixed to the rail and extending inwardly, a lever secured to the border wire and extending inwardly and downwardly, a link having one end pivoted to the support adjacent the rail and its other end pivoted to the lever adjacent its inner end, and a spring having its ends abutting the inner ends of the lever and support and being secured thereto.

5. In a bed spring having a side rail and a border wire, a border brace including a support fixed to the rail and extending inwardly, a lever secured to the border wire and extending inwardly and downwardly, a link having one end pivoted to the support adjacent the rail and its other end pivoted to the lever adjacent its inner end, and a spring having its ends abutting the inner ends of the lever and support and being secured thereto; the brace being so proportioned that it will cause the border wire to move downwardly in substantially a vertical plane when depressed.

6. In a bed spring having a side rail and a border wire, a border brace including a support having a bent end fixed to the rail and a body part extending horizontally inward, a lever fixed to the border wire and extending downwardly and inwardly and terminating in a horizontal part, a link having one end pivoted to the support adjacent its bent end and its other end pivoted to the lever near the junction of its inclined and horizontal parts, and a tight spiral spring acting as a stop between the inner ends of the lever and support and connected to said ends for yieldingly holding them against the ends of the spring.

In testimony whereof I have signed my name to this specification.

ROWLAND STANERT.
